JACOB GRASS, OF FULHAM, LONDON, ENGLAND.

LITHOGRAPHIC PLATE FOR OFFSET AND DIRECT PRINTING.

1,155,352.

Specification of Letters Patent.

Patented Oct. 5, 1915.

Application filed July 24, 1914. Serial No. 852,867.

REISSUED

To all whom it may concern:

Be it known that I, JACOB GRASS, subject of the German Emperor, residing at 104 New King's road, Fulham, London, England, have invented certain new and useful Improvements in and Relating to Lithographic Plates for Offset and Direct Printing, of which the following is a specification.

10 This invention relates to the production of metal lithographic plates, and its object is to enable the plate to carry more ink than hitherto, thereby imparting a deeper color to the print obtained from the plate, either 15 directly or through the medium of an offset surface.

In the usual method of providing a metal lithographic plate with a printing surface, the greasy printing surface is applied to the 20 surface of the plate by means of a transfer, obtained in the well-known manner, whereafter the surface of the plate surrounding the various portions of the printing surface, is cleaned from scum by means of a liquid. 25 This latter treatment is called etching, although not etching in the literal sense. The printing surface of an ordinary metal lithographic plate consists of a greasy substance on the surface of the plate.

30 Now according to the present invention, the printing surface of a metal lithographic plate is etched intaglio into the plate, whereby the printing surface, consisting of intaglio recesses, can take up and impart more 35 ink, than the mere "surface" printing surfaces hitherto provided on lithographic plates.

The intaglio printing surface is formed on the metal lithographic plate, by printing 40 photographically through a positive transparency on a sensitized colloid film coating the plate, and afterward etching the plate through the exposed and treated film.

The figure of the drawings is an illustration on an enlarged scale of a lithographic plate made in accordance with the invention.

In said figure the numeral 1 designates a thin flat plate of metal which forms the ordinary lithographic plate, such as zinc or aluminum, having a groove or depression 2. therein, constituting an intaglio portion of the plate which is coated with varnish as shown at 3 within said groove, said coating 50 of varnish covering the bottom of the depression, while the ink designated by the nu-

merals 4 is filled into the groove over the varnish which serves as a mat to hold a maximum quantity of the ink and which extends to the surface of the plate.

The process is as follows:—A zinc or aluminum lithographic plate is coated with a sensitive colloid film, such as fish glue sensitized with a bichromate. A positive transparency, rendered suitably opaque, is placed on the sensitized film. For producing a direct printing plate the transparency is placed face downward on the plate, for producing an offset printing plate, the transparency is placed face uppermost and away 70 from the plate, the transparency being suitably thin. On exposure to light, the portions of the sensitized coating of the plate which are beneath the transparent portions of the transparency harden. After removal 75 of the transparency, the plate is washed with water which dissolves away the unhardened portions of the coating of the plate, and the plate is dipped in a dye bath, for instance a bath of methyl violet dye, 80 to render the picture or the like now on the plate visible. After being dried, the plate is immersed from 2-3 minutes in an etching bath, for instance a perchlorid of iron bath. The usual etchers' precautions in having the 85 etching liquid of the correct consistency should be observed. After etching, the hardened glue or the like film is softened by diluted hydrochloric acid or other means, and the plate is dried. The intaglio portions of the plate can then be filled in with lithographic ink, but to cause the ink to hold 90 better in the recesses, and impart a deeper color to the print obtained from the plate a varnish which is not dissolved by water or grease, such as celluloid varnish, is first rubbed into the recesses or intaglio portions of the plate. Celluloid varnish being a mat varnish also provides a holdfast for the ink which enters into the pores thereof. The 95 celluloid varnish is rubbed or worked in by means of a cloth and the ink is then rolled into the varnished intaglio recesses. The glue or like film is then washed away by sponging the plate with water. The plate 100 is now gummed over with gum-arabic or the like to prevent oxidation, and is then ready for the machine.

The positive transparency may be produced by photography, by direct impression 110 from a printing surface, such as a half-tone block or set-up type, by type-writing or

other suitable manner and rendered sufficiently opaque by dusting over with a suitable powder. The positive transparency can for example be produced by making an 5 impression from a printing surface upon gelatin tracing paper, or this medium has the type-written matter directly typed thereon. The transparency is then dusted over with an opaque powder, such as powdered 10 graphite, bronze, silver or the like powder, which, owing to the powder adhering to the varnish of the impression or typed matter, renders the same opaque.

I claim:

15 1. A method of producing a printing surface on a metal lithographic plate, consisting of coating said plate with a sensitized film, exposing said film to light through a positive transparency, washing said plate after 20 removal of said transparency, drying said plate, etching said plate, softening said film after said etching and removing the same, drying said plate, applying varnish insoluble in water or grease to the etched recesses 25 of said plate, and filling said recesses with lithographic ink to a plane coincident with the face of the plate, said varnish serving as a mat to hold a maximum quantity of ink, thereby imparting a deeper color to the 30 print obtained from the plate.

2. A method of producing a printing surface on a metal lithographic plate, consisting in coating said plate with a sensitized colloid film, exposing said film to light 35 through a positive transparency, washing said plate after removal of said transparency, drying said plate, etching said plate, softening said film after said etching, drying said plate, applying celluloid varnish to 40 the etched recesses of said plate and filling said varnished recesses with lithographic ink and removing the film.

3. A method of producing a printing surface on a metal lithographic plate, consisting in coating said plate with a sensitized film, exposing said film to light through a transparency, washing said plate after removal of the transparency, drying said plate, etching said plate, softening said film 45 after said etching, drying said plate, applying celluloid varnish to the etched recesses of said plate, filling said varnished recesses

with said lithographic ink, removing said film by washing around the recesses and gumming said plate to prevent oxidation. 55

4. The process of producing an intaglio printing surface on a metal lithographic plate, consisting in coating the same with a sensitized colloid film in the form of a glue, placing a positive transparency on the sensitized film rendered suitably opaque, hardening the portions of the sensitized coating of the plate which are located beneath the transparent portions of the transparency, dissolving away the unhardened portions of 60 the coating of the plate by washing with water, dipping the plate in a dye bath to render the picture or the like thereon visible, drying the plate, immersing the same in an etching bath, softening the hardened glue like film and removing the same, then drying the plate and filling the intaglio portions of the plate with lithographic ink. 65

5. The process of producing an intaglio printing surface on a metal lithographic 75 plate, consisting in coating the same with a sensitized colloid film in the form of a glue, placing a positive transparency on the sensitized film rendered suitably opaque, hardening the portions of the sensitized coating of 80 the plate which are located beneath the transparent portions of the transparency, dissolving away the unhardened portions of the coating of the plate by washing with water, dipping the plate in a dye bath to 85 render the picture or the like thereon visible, drying the plate, immersing the same in an etching bath, softening the hardened glue like film, removing said film, then drying the plate and working celluloid varnish 90 into the intaglio portions of the plate and then filling said intaglio portions with lithographic ink over the said varnish, whereby the latter being a mat varnish, will cause the ink to enter the pores thereof to produce a deeper color than is otherwise obtainable. 95

In testimony whereof I affix my signature in presence of two witnesses.

JACOB GRASS.
